United States Patent Office

Des. 196,866
Patented Nov. 12, 1963

196,866

COMBINED PITCHER AND COVER THEREFOR

Jerome Lewis, 230 5th Ave., New York, N.Y.

Filed Dec. 31, 1962, Ser. No. 72,990

Term of patent 14 years

(Cl. D44—21)

FIG. 1

FIG. 2

FIG. 3

FIG. 4

FIG. 5

FIG. 6

FIG. 1 is a front elevational view of a combined pitcher and cover therefor embodying my new design;

FIG. 2 is a side elevational view thereof; the opposite side being identical with the side shown;

FIG. 3 is a top plan view thereof;

FIG. 4 is a bottom plan view thereof;

FIG. 5 is a rear elevational view thereof; and

FIG. 6 is an exploded front elevational view thereof, with the cover lifted off the pitcher.

I claim:

The ornamental design for a combined pitcher and cover therefor, as shown.
